UNITED STATES PATENT OFFICE.

ISIDOR KITSEE, OF PHILADELPHIA, PENNSYLVANIA.

ELECTRIC TELEGRAPHY.

No. 821,506.

Specification of Letters Patent.

Patented May 22, 1906.

Application filed August 26, 1905. Serial No. 275,958.

To all whom it may concern:

Be it known that I, ISIDOR KITSEE, of the city and county of Philadelphia and State of Pennsylvania, have invented certain new and useful Improvements in Electric Telegraphy, of which the following is a specification.

My invention relates to an improvement in telegraphy, and has more special reference to telegraphing over lines with comparative great capacity—such, for instance, as submarine or subterranean cables.

The peculiar conditions which are met with in the transmission of electricity through long submarine lines render it necessary to use in transmitting messages according to the method now in general use the so-called "double key," whereby impulses of one polarity are transmitted to denote a dot and impulses of a second polarity are transmitted to denote a dash. With the aid of this double key if the code to be transmitted consists alternately of dots and dashes the ideal "clearing" of the line would be reached. In reality the code never consists of alternating dots and dashes; but, on the contrary, in nearly every word or syllable two or more dots or two or more dashes are grouped together, and impulses of one polarity have to be transmitted in succession without an opportunity being given to "clear" the line. This drawback is readily realized by persons versed in the art; but no efficient arrangement to overcome this difficulty has been practiced, and it is the aim of my invention to provide means whereby this disadvantage is overcome.

To clearly understand my invention, it is necessary to understand the action of condensers. The first of these facts is that if a condenser is connected to a source of straight or unidirectional current—such, for instance, as a battery—a momentary impulse of electric energy will pass by inductive influence through the condenser, charging the same, but will cease as soon as this charging is complete.

The usual test with a galvanometer, the needle of which will deviate from the zero-point at the moment the circuit is closed, but will return after a very short period to its zero position, will prove the correctness of this assertion. Second, a condenser once charged has to be first discharged before a second impulse of the same polarity will pass through same and through the line. Third,

the discharging of a condenser through a resistance takes an appreciable time, and the greater the capacity of the condenser and the greater the resistance through which such discharge takes place the longer the time unit for such discharge. Fourth, to entirely clear a condenser from a charge of one polarity it is best to send a charge of opposite polarity through the same. Therefore to work over lines of great capacity—such, for instance, as a submarine cable, which may be likened to a long-drawn-out condenser—it is best, as said above, to employ alternating impulses of opposite directions or polarities. The ideal telegraphing over such cables would therefore be in the sending of impulses always of the same duration and intensity, but alternately of opposite polarities, over the line. Such method would be adopted were it not for the reason that the Morse characters, Continental as well as American, consist of dots and dashes, and the impulses have to symbolize the difference between these two characters. The nearest approach thereto in cable telegraphy, as said above, is the employment of the double key and the sending of an impulse of one polarity to denote a dot and an impulse of the opposite polarity to denote a dash; but the frequent recurring of two or more dots or two or more dashes in succession spoils the usefulness of this method. This necessitates the sending of two or more impulses of one polarity over the line in succession, which, as pointed out before, is a great drawback in telegraphy over cables.

Referring now to the drawings, Figure 1 and Fig. 3 are diagrammatic views illustrating my invention, and Fig. 2 is a perspective view of part of the well-known siphon-recorder.

L is the line of transmission, here shown in dotted lines. This line is connected on one side with the transmitting device, comprising the condenser C', connected through wire 5 with the battery B'. This battery is in electrical connection, through wire 4, with the resistance R, connected in turn through wire 3 with one pole of the battery B, the other pole of which is connected, through wire 2, with the condenser C, grounded through wire 1 at G. To wire 4 is connected wire 7 and to this wire the lever A of a common transmitting-key. To wire 2 is connected wire 6, and thereto the contact-point a for said key. The transmitting device,

therefore, consists of the two sources of current B and B', which, as illustrated in the drawings, are connected in opposition as to each other. The source B is here shown as 5 to consist of four cells, and the source B' as to consist of two cells. The transmitting device further consists of the two condensers C and C' and the common transmitting-key A. At the other terminal the line is connected to the receiving device, consisting of the polarized relay D, embracing the two electromagnets d and d', the polarized armature E, and the two adjustable stops e and e': The stop e is preferably made of insulating 15 material and the stop e' of conducting material. This relay is connected, through wire 8, if required, with the interposition of necessary other instruments, to the ground G'. Preferably connected to this relay is the translating device—such, for instance, as the sounder F, provided with the armature f, held by the spring f² against the upper stop f². The armature f is also provided with the lower stop f'. The coil of this device forms, 20 through wire 9, battery B², and resistance R', a local circuit normally closed. I provide this circuit for convenience with the switch S.

One terminal of the resistance R' is connected, through wire 10, with the stop e' and 30 the other terminal of said resistance through wire 11 with the armature E.

I designate the transmitting-station as an entirely by the letter X and the receiving-station by the letter Z.

35 It is supposed that the device X is connected to the line and the lever A of the key is out of contact with the stationary point a. The shunt, therefore, consisting of wires 6 and 7, A and a around the battery B and the resistance R, is open, and as the battery B consists of four cells and the battery B' of only two cells connected in opposition as to the four cells of B it is obvious that only one-half of the force of B is available, as the other half 45 is neutralized by the two cells of B'.

At the moment of connecting the device X to the line and ground, respectively, a current impulse will therefore charge the condensers equal to two cells, but flowing in the 50 direction of the feathered arrow. This impulse is, as said above, only momentary, and the line after this impulse is passed will be free from electrical disturbance. At the receiving side the polarized relay D is connected to the line and ground in a manner so that this impulse should send the armature toward and in contact with the stop e. As this stop is non-conducting and does not connect with any translating device, it is obvious that through this impulse none of the translating devices will be actuated, and I call this impulse the "clearing" or "spacing" 55 impulse. It is now supposed that the operator at the transmitting-station desires to 60 transmit an impulse to the receiving-station 65

Z, which impulse should be felt and recorded at said station. He presses the key-lever A till it comes in contact with the contact-point a. Through this connection a shunt is established around the source B. The current, 70 therefore, of this source will not be able to oppose the flow of the current from B', and the condensers C and C' will now be charged in the direction opposite to the direction of the former impulse or in the direction of the 75 unfeathered arrow. This impulse flowing over the line will move at the receiving-station Z the armature E of the device D from the stop e to the contact e', thereby establishing a shunt around the resistance R'. 80 The translating device F is, as was formerly stated, connected with the interposition of the resistance R' to the battery B²; but the value of the resistance R' is so high that the force of the battery B² is not enough, as long 85 as this resistance is in the circuit, to energize the core sufficiently for the purpose of actuating the armature f; but when through this impulse the armature E of the device D is made to come in contact with the stop e a 90 shunt is established around the resistance R', consisting of the wire 10, contact e', armature E, and wire 11. The force of the battery B² is now great enough to sufficiently energize the core and to make operative its 95 armature f. The operator at this station will therefore know that the transmitting operator has transmitted one impulse over the line. Let us now suppose that the operator at X holds the lever of the key down for 100 an indefinite period. No impulse will be made to flow through this extended pressure, for the reason that, as said above, the condensers C and C' being charged they will prevent the flow of the current from B', but at 105 the receiving-station the armature E will still rest at and connect with the contact e'. The resistance R' will therefore be still short-circuited, and the force of the battery B² will still energize the core of F, and the armature 110 f will still be drawn downward and in contact with the stop f'. No matter, therefore, how long the pressure of A on point a continues, the electrical as well as mechanical conditions of the line will remain stationary; but 115 at the moment the operator releases the key the shunt around the source B is opened, and as its force is double the force of the source B' an impulse of opposite polarity, but of the same intensity as before, will 120 charge the condensers C and C'. This impulse flowing also over the line in opposite direction will remove the armature E from the contact e' and bring the same against the stop e.

125 It may be stated that as the line is normally grounded at both the receiving and transmitting end it would seem that the condensers would be discharged as soon as they are charged, and therefore a continuous flow 130

of current may result; but experiments have proven that in a long line or a line having a great resistance the earth connection does not discharge the condenser if the same is 5 not directly placed to the ground or shunted with a very low resistance.

I have established a long line embracing a variable resistance of from ten thousand ohms up to one hundred thousand ohms and 10 connected the same in substantially the same manner as is illustrated in Fig. 1 with substantially the same devices. The battery B consisted of four dry cells and the battery B' of two dry cells. The resistance 15 R had a value of about fifty ohms, and each of the condensers C and C' had a capacity of one microfarad. The resistance of the coils of the relay D was about twelve thousand ohms. The connection to the ground was 20 made on one side through a water-pipe and on the other side through a large metallic plate. In this circuit was placed a sensitive galvanometer answering at one volt to three megohms. When the connections of the 25 line were made, the needle deviated to the right, but only momentarily, and then came again after a few deflections to its zero position. When the key was depressed, the needle deviated to the left and came again after 30 a few deflections to its zero position, thus showing that after the first impulse the line was free from all electric energy.

The second test was as follows: When 35 through the force of the unshunted battery B the condensers C and C' were charged and the armature E moved to the stop e, the armature was then by hand removed from e and placed in connection with contact e' and the same remained as placed, proving that 40 there was no appreciable electric force flowing over the line. It will thus be seen that the closing of the key will send an impulse of electric energy over the line of the same duration and substantially the same intensity 45 as the opening of the key but of opposite polarity and that the time the key remains open or closed does not effect the electrical condition of the line at all.

It is now necessary to explain how the 50 transmitting operator differentiates between sending a dot and dash and how the receiving operator can distinguish between these two impulses when receiving the same. For the sake of illustration it is assumed that the operator desires to transmit the letter "E," 55 consisting, as is well known according to the American Morse, of one dot. The operator closes the shunt-circuit by pressing the lever A of the key, but releases the same after a 60 short period equal to one unit of time in the Morse alphabet. Through the pressing of the lever A the shunt around the battery B is established and an impulse will flow over the line in the direction of the unfeathered 65 arrow. The armature E at the receiving-

station will connect with the stop e', thereby making operative the device F. If this device is a common sounder, then the armature will make the usual downstroke and in the usual unit of time the upstroke. The operator versed in the Morse alphabet will readily recognize this impulse as one dot, or the letter "E." Should the operator at X desire to transmit the letter "I," consisting of two dots, then he presses and releases the lever A 70 twice in comparative quick succession. Translated at the receiving-station it will result in two short downstrokes, each followed in quick succession by an upstroke. It will readily be recognized by the receiving operator as two dots or the letter "I." Now should the operator desire to transmit the letter "T," consisting of one dash, he presses 75 the key as usual, but continues this pressure for a greater length of time. 80

It was stated above that through the closing of the key the armature E at the receiving-station will be moved toward and in contact with e'. This armature will remain at rest at e' until the key is again opened, for the 85 reason that there is no power present to remove this armature from its resting-place, and this power will not be exerted till the sending operator releases his key. The downward stroke of the armature of the device F will therefore not be succeeded by an 90 upper stroke in quick succession, but only after an appreciable time has lapsed and the Morse operator recognizes this as a dash. 95

Should the transmitting operator desire to 100 transmit the letter "M," consisting of two dashes, then he presses the key twice in succession; but each time the pressure must last for a time longer than the time unit representing a dot. In reality the exact time 105 units adopted by the Morse may also be adapted with this my invention. In other words, a dot is symbolized by the closing of the key for one unit of time, the dash is symbolized by the closing of the key for nearly 110 three units of time, the space between the elements of each letter is characterized by one unit, and the space between two letters is characterized by nearly three units, and the space between two words by about five 115 units.

The difference between the common Morse telegraphy and telegraphing according to my system lies essentially in the following particulars: With the ordinary land Morse the operator sends a short impulse over the line for a dot and a long impulse over the line for a dash. With my invention the operator sends a short inductive impulse for a dot as well as for the dash; but he differentiates these two characters—dot and dash—by simply preventing for a longer or shorter time the flow of an opposite impulse over the line, and as to remove the armature E from the contact e' it requires this opposite impulse it is self-evident 125 130

that the device at the receiving-station will register in accordance with the length of time that the transmitting operator holds the key down—that is, will register a short 5 mark for a dot and a longer mark for a dash, or when the receiving instrument consists of a sounder it will hold the armature down a short time for a dot and a longer time for a dash.

10 The spacings between the different characters, letters, and words are signified by the shorter or longer time the operator allows the key to remain open, for as the opening of the key will drive the armature E at the receiving-station toward the stop e this armature will remain there until an opposite impulse passes the line, and as this opposite impulse cannot pass the line before the closing of the key it is obvious that the shorter or longer 15 time that the operator allows his key to be opened will result at the receiving-station in a shorter or longer time of inoperativeness of the receiving device, thereby signifying a space between letters, elements, or words, as 20 the case may be. With this arrangement a common sounder may, as said above, be employed even in submarine telegraphy as a receiver, and it is self-evident that such devices may easily be used as a relay or repeater to 25 automatically transmit the messages from one cable to another or from one cable to land-lines, or vice versa.

In Fig. 3 I have illustrated the device F as performing such a function, and in this figure 30 similar letters as in Fig. 1 are used to designate similar parts. It has only to be borne in mind that the device F is part of one line and its accessories and operates a second line with its accessories. In the drawings the device F operates a shunt similar to the shunt in 35 Fig. 1 and consisting of the battery B , resistance R , and the wires 6 and 7; but instead of the lever A and the conducting-point a , as in Fig. 1, the shunt is opened and closed by the 40 operation of the armature f and the contacting of the same with the stops f' or f'' .

In Fig. 2 I have illustrated part of the well-known siphon-recorder, which may be actuated in accordance with my invention. I 45 designate the same as an entirety by the letter H , the siphon proper by the letter h , and the stops between which the siphon may vibrate as h and h' . I designate the shield by the letter I and provide the same with the 50 perforation I' . K represents the paper tape whereon the characters received are adapted to be recorded.

The operation of a siphon-recorder is well understood and does not need to be repeated 55 here. The purpose of the shield I is to prevent the ink from being deposited on the paper except when the end of the siphon is directly over the perforation I' . Now as the siphon is held in a manner so as to rest normally at one or the other of the stops h or h'

it is obvious that if an impulse sent over the line will move the siphon—say to the right—then the end of the same will come over the perforation and the ink will be deposited on the paper; but if the impulse sent over the line moves the siphon toward the stop h then the end of same will not come directly opposite the perforation, and the depositing of the ink on the paper will be prevented.

Having now described my invention, what 75 I claim as new, and desire to secure by Letters Patent, is—

1. A telegraph-line having two unequal sources of electromotive force connected therein in opposition to each other, means 80 comprising a single contact-key connected to said line with respect to said sources of electromotive force to cause the transmission of an electrical impulse of one polarity to line when the contact of said key is closed and an 85 impulse of an opposite polarity to line when said contact is opened, and static means acting independently of said key to automatically limit the duration of said impulses.

2. A telegraph-line having two unequal 90 sources of electromotive force connected therein in opposition to each other, a shunt around one of said sources, means to vary the resistance of said shunt in the transmission of signals, and static means to automatically 95 limit the duration of the signaling impulses which pass to line.

3. A telegraph-line having two unequal sources of electromotive force connected 100 therein in opposition to each other, a shunt 105 around one of said sources, means to vary the resistance of said shunt in the transmission of signals, and static means acting independently of the resistance-varying means to automatically limit the duration of the signaling 110 impulses passing over the line.

4. A telegraph-line having two sources of unequal electromotive force connected therein in opposition to each other, a single contact Morse key connected in the shunt 115 around one of said sources, and a capacity connected in series between the terminals of said sources from which emanate impulses of the same polarity.

5. A telegraph-line having two sources of unequal electromotive force connected therein in opposition to each other, a single contact Morse key connected in shunt around one of said sources, a capacity connected in 120 series between the terminals of said sources from which emanate impulses of the same polarity, a polarized receiving-relay having its coils connected in series with the main line, a resistance connected in series with the tongue and one contact of said relay, a closed 125 circuit connected in shunt around said resistance, and a translating device connected to be operated by current in said shunt, substantially as described.

6. In telegraphy two sources of current 130

connected normally in series as to each other and the line with the interposition of a condenser or condensers, one source adapted to furnish the signaling energy and the second adapted to furnish the spacing energy and means to shunt one of said sources in accordance with the impulses to be transmitted.

7. A system of telegraphy consisting of the line proper, a transmitting-station and a receiving-station connected to said line proper, the transmitting station embracing two sources of current, one of substantially double the strength of the other, the two sources connected in opposition as to each other, condenser or condensers interposed between said sources line and ground, a shunt around one of said sources and means to open and close said shunt in accordance with the characters to be transmitted, the receiving-station comprising a polarized relay and a translating device operatively connected to said relay.

8. In a system of telegraphy two sources

of current, one of higher electromotive force than the other, said sources oppositely connected to each other, and means to shunt the source of higher electromotive force, said shunt embracing a transmitting-key and a resistance.

9. A transmitting device in electric telegraphy embracing two sources of current connected in opposition as to each other, the electromotive force of one source greater than the electromotive force of the second source, means to shunt the source of greater electromotive force and means to prevent the flow of current from any of said sources except for a short impulse due to the change in one of said sources.

In testimony whereof I hereby sign my name, in the presence of two subscribing witnesses, this 24th day of August, A. D. 1905.
